(57) **CLAIM**

The ornamental design for a UV advanced oxidation process reactor, as shown and described.

DESCRIPTION

FIG. 1 is a top perspective view of a UV advanced oxidation process reactor;

FIG. 2 is a front elevational view of the UV advanced oxidation process reactor;

FIG. 3 is a rear elevational view of the UV advanced oxidation process reactor;

FIG. 4 is a left side elevational view of the UV advanced oxidation process reactor;

FIG. 5 is a right side elevational view of the UV advanced oxidation process reactor;

FIG. 6 is a top plan view of the UV advanced oxidation process reactor; and,

FIG. 7 is a bottom plan view of the UV advanced oxidation process reactor.

Broken lines illustrate portions of the UV advanced oxidation process reactor that form no part of the claimed design.
